Des. 471

Samuel D. Vose of Albany, N.Y.

Letters Patent No 471 Dated July 13th 1852

The schedule referred to in these Letters Patent and making part of the same
To all whom it may concern:

Be it known that I, Sam'l. D. Vose, of Albany, County
of Albany and State of New York, have invented or produced a new ornamental
design for an Air Tight Cook Stove, and I do hereby declare that the following
is a full and exact description of the same, reference being had to the annexed
drawings affixed and making part of this specification.

Fig 1. Represents the stove perspective

"	W.	"	Back
T	"	"	Top
F	"	"	Front
H	"	"	Hearth
L	"	"	Legs
S	"	"	Side and doors

The side not seen in the drawings is fac simile to the side shown.

My invention consists in the combination of the several mouldings
and ornaments as arranged in the whole stove & is not easily described in words &
reference is therefore made to the drawings.

I do not claim any detailed part of the mouldings, or configuration.

What I claim as my invention and desire to secure by Letters Patent
is the combination of the several mouldings and ornaments as arranged together,
the whole forming an ornamental design for an air tight cook stove, as herein set
forth & described

James N. Adams
E. Prendergast

Sam'l. D. Vose
